UNITED STATES PATENT OFFICE.

GEORGE W. WALTON, OF GRAYLING, MICHIGAN.

DESIGN FOR A CAN.

SPECIFICATION forming part of Design No. 20,562, dated March 3, 1891.

Application filed January 26, 1891. Serial No. 379,175. Term of patent 7 years.

To all whom it may concern:

Be it known that I, GEORGE W. WALTON, a citizen of the United States, and a resident of Grayling, in the county of Crawford and State of Michigan, have invented certain new and useful Improvements in Cans for Caking Ice, &c.; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a side view, and Fig. 2 is a top plan view.

This invention relates to new and original designs for cans; and it consists in the novel form and configuration of parts, as hereinabove set forth.

20 The leading feature of my design consists in the rectangular form of the can, as shown in Fig. 1, with the lugs or bosses at each upper corner, which when viewed in plan, as shown

25 in Fig. 2, conform to the shape of the angular portion of the can, these bosses being of the thickness of the body material of the can and following its contour for about one-tenth each

way from the line of intersection of two sides of the can, thus forming four projections. 30

The body of my design is of a hollow prismatic outline open at the top, with the lateral edges of the prism rounded. The superior edges of the prism are cut at right angles to the plane of the top at each corner, and the 35 four sections thus formed are turned outward and downward, forming the rounded edges A A. (Shown in Fig. 1.) The faces of the prism forming the bottom of the can are also shown as tapering slightly from the top to bottom. 40

At the central portion of two opposite outer faces of my design are arcuate projections C C. The central portions of these arcuate projections are rounded, and their upper and lower edges are turned outward and then inward, forming a flange projecting angularly outward from the rounded central portion B. 45

What I claim is—

The design for cans herein shown and described. 50

In testimony whereof I affix my signature in presence of two witnesses.

GEORGE W. WALTON.

Witnesses:

J. A. LEONARD,
W. A. MARTIN.
